(57) **CLAIM**

The ornamental design for a smart lock, as shown and described.

DESCRIPTION

FIG. 1 is a perspective view of a first component of a smart lock, shown separately for ease of illustration;

FIG. 2 is a front view of the front panel of FIG. 1;

FIG. 3 is a rear view of the front panel of FIG. 1;

FIG. 4 is a left side view of the front panel of FIG. 1;

FIG. 5 is a right side view of the front panel of FIG. 1;

FIG. 6 is a top view of the front panel of FIG. 1;

FIG. 7 is a bottom view of the front panel of FIG. 1;

FIG. 8 is a perspective view of a second component of a smart lock, shown separately for ease of illustration;

FIG. 9 is a front view of the rear panel of FIG. 8;

FIG. 10 is a rear view of the rear panel of FIG. 8;

FIG. 11 is a left side view of the rear panel of FIG. 8;

FIG. 12 is a right side view of the rear panel of FIG. 8;

FIG. 13 is a top view of the rear panel of FIG. 8;

FIG. 14 is a bottom view of the rear panel of FIG. 8; and,

FIG. 15 is a schematic view of the first component and the second component of the smart lock shown in a position of use.

The portions shown in broken lines form no part of the claimed design.

1 Claim, 15 Drawing Sheets
